TIE TACK OR SIMILAR ARTICLE

Italo Rotondo, 59 Smart St., Providence, R.I. 02904

Filed Dec. 16, 1968, Ser. No. 14,997

Term of patent 14 years

Int. Cl. D2—08

U.S. Cl. D2—419

FIG. 1

FIG. 2

FIG. 3

FIG. 4

FIG. 5

FIG. 6

FIG. 1 is a front elevational view of a tie tack or similar article, showing my new design;

FIG. 2 is a side elevational view thereof looking from the left with respect to FIG. 1;

FIG. 3 is a side elevational view thereof looking from the right with respect to FIG. 1;

FIG. 4 is a rear elevational view thereof;

FIG. 5 is a top plan view thereof; and

FIG. 6 is a bottom plan view thereof.

I claim:

The ornamental design for a tie tack or similar article, substantially as shown.
